UNITED STATES PATENT OFFICE.

SYDNEY I. PRESCOTT, OF NEW YORK, N. Y.

INTERNAL-COMBUSTION ENGINE.

1,224,566.

Specification of Letters Patent.

Patented May 1, 1917.

Application filed November 16, 1915. Serial No. 61,737.

To all whom it may concern:

Be it known that I, SYDNEY I. PRESCOTT, a citizen of the United States, residing at New York, county of New York, and State 5 of New York, have invented a new and useful Improvement in Internal-Combustion Engines, of which the following is a specification.

This invention relates to an improvement 10 in internal combustion engines, particularly to those of the multi-cylinder two-cycle type.

In two-cycle engines heretofore employed, it has been customary to introduce a charge 15 of fresh gas into the combustion chamber of the cylinder while the chamber was filled with flaming gas passing out through the exhaust port, the greater speed of the exhaust being relied upon to prevent ignition of the 20 incoming charge. The present invention has for one of its objects the production of a two-cycle engine in which a scavenging charge of clean air preferably under pressure is introduced into the combustion 25 chamber after the exhaust port has opened and before a charge of fresh gas flows into the chamber. This is for two distinct purposes: first, to drive the burned gas out of the cylinder in decreased time as the pressure within the cylinder falls; and second, 30 to form a cloud or barrier of clean air between the outgoing flaming gas and an incoming charge of fresh gas particularly when, as in the present instance, the incoming 35 charge of fresh gas flows at high speed.

The speed of two-cycle engines heretofore employed has been limited because, among other reasons, of the limited time available for exhausting the burned gas 40 from the cylinder and introducing a charge of fresh gas. The present invention has for another of its objects the production of a two-cycle engine in which the initial pressure of the charge of fresh gas is greatly increased over that heretofore found possible in this type of engine so that the transfer of the fresh gas from the induction chamber to the combustion chamber is made in much less time than has heretofore been possible. 45 Due partly to the quicker expulsion of burned gas from the cylinder by the use of scavenging air under pressure, and partly to the quicker transfer of the fresh gas from the induction chamber to the combustion 50 chamber of the cylinder, which is made pos-

sible by the use of the barrier of clean air in the cylinder between the outgoing flaming gas and the incoming fresh gas and by the higher initial pressure of the fresh gas charge, higher engine speed is attained. 60

In certain types of two-cycle engines heretofore used, fresh gas has been pumped into the crankcase, therein compressed slightly, and then transferred to the combustion chamber solely through ports or passages 65 uncontrolled by any valve mechanism. In certain other types the initial charge of fresh gas has been drawn into and compressed in the lower part of one cylinder, and then transferred to the combustion 70 chamber of another cylinder, this transfer being effected through the agency of suitable passages and a distributor valve. The present invention has for another of its objects the production of a two-cycle engine in 75 which an induction chamber is formed within a piston, fresh gas being drawn into this chamber by the movement of the piston in one direction, compressed therein during the movement of the piston in the opposite direction, and then transferred through a suitable port in the wall of the piston and short by-pass passages to the combustion chamber and the cylinder in which the piston works, 80 the time of the transfer being controlled by 85 a rotary valve.

Another object of the invention is the production of a two-cycle engine of the general character just described, in which a single valve not only controls the transfer of fresh 90 gas from the induction chamber to the combustion chamber, but also controls the intake of fresh gas to the induction chamber and further controls the introduction of scavenging clean air into the combustion chamber 95 just prior to the transfer of a charge of fresh gas.

With these and other objects not specifically mentioned in view, the invention consists in certain parts, constructions and 100 combinations which will be hereinafter fully described and then specifically set forth in the claims hereunto appended.

In the accompanying drawings, which form a part of this specification and in 105 which like characters of reference indicate the same or like parts, Figure 1 is a sectional elevation through one cylinder of a multi-cylinder engine constructed in accordance with the invention; Fig. 2 is a plan view of 110

the structure shown in Fig. 1, partly shown in full plan, partially broken away, and partly taken on the sectional lines indicated at B B, C C and D D in Fig. 1; and Figs. 5 to 10 inclusive are diagrammatic fragmentary views illustrating the operation of the device shown in Figs. 1 and 2.

In carrying the invention into effect, there is provided a source of gas supply, a cylinder having a combustion chamber, a piston having a wall port and working within the cylinder, means coöperative with the piston to form an induction chamber within the piston, and means coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke. In the best constructions, there is also provided a source of clean air supply and means for introducing clean air into the combustion chamber of the cylinder after the exhaust port has opened and the flaming gas has begun to flow outward and before a charge of fresh gas begins to flow into the combustion chamber. In the best constructions also, a rotary valve and coöperative by-pass mechanism is utilized for the purpose of controlling the inflow of gas to the induction chamber, the inflow of clean air to the combustion chamber for scavenging purposes, and the transfer of the fresh gas from the induction chamber to the combustion chamber. In the best construction also, the induction chamber is formed within the piston by a device which is piloted in one end of the cylinder and which projects into the piston. In the best constructions also, this device is also operative as a crosshead guide and a crosshead works within this device, connection being made between the crosshead and the piston by a piston rod passing through a stuffing-box formed in said device. All of the above mechanisms and devices may be varied in construction within wide limits. The invention selected to illustrate the invention is but one of many possible concrete embodiments of the same and the invention therefore is not to be restricted to the precise details of the structure shown and described. Furthermore, certain parts of the invention are capable of use independent of other parts, and such independent use is contemplated.

Referring to the drawings, 1 indicates the upper part of a crankcase casting which is of well known construction and is therefore merely indicated in the present drawing.

Supported by the crankcase 1 is a block casting 2 having a number of cylinders 3 formed therein. The block casting 2 is held

in place upon the crankcase 1 by means of holding bolts 4 of well known construction. The upper end of the block casting 2 is fitted with a casting 5, and the casting 5 is held in place in a well known manner by means of bolts 6. This casting 5 forms the heads of the cylinders 3. Surrounding the upper part of the cylinders 3 is a water jacket marked 7 and this water jacket opens through suitable apertures 8 into a water jacket 9 formed in the casting 5 before referred to. An inlet for the water is provided at 10 near the lower end of the water jacket, and an outlet for the water is provided at 11 which is an extension of the water jacket 9 within the casting. The casting 5 is provided with threaded apertures 12 above each cylinder adapted to receive spark plugs. Of course, air cooling means may be used in place of the water system, if desired.

Working within each cylinder 3 is a piston 13 having a pair of elongated ports 14 in one side thereof. These ports are always in register with an intake port 15 cored in the casting 2 and opening into a valve chamber 16 located beyond the water jacket 7 on one side of the casting. Above the intake port 15 is cored a by-pass port 17 which opens into the interior of the cylinder 3 and the interior of the valve chamber 16. Upon the opposite side of each cylinder is located an exhaust port 18 cored in the casting 2 and extending through the outer wall of the water jacket 7 where it may be connected with a suitable manifold, not shown. By an inspection of Fig. 1, it will be seen that the port 18 is a little higher than the by-pass port 17 and considerably higher than the intake port 15.

Located immediately below the valve chamber 16 is a gas manifold 19 ported at 20 into the valve chamber. It will be understood that this valve chamber and manifold extend along or across all of the cylinders, and that the manifold 19 is ported into the valve chamber opposite each cylinder. A pad or boss 21 is provided in the lower wall of the manifold 19 to which a carbureting device may be attached.

Above the valve chamber 16 is a clean air manifold 22 ported into the valve chamber 16 at 23 opposite each cylinder, and provided with a pad or boss 24 to which a suitable pipe may be secured.

Located within the valve chamber 16 is a rotary valve 25, this valve having a central aperture 26 and being designed to be rotated in the direction of the arrow by mechanism not shown but well known in the art, the speed of rotation being the speed of the crankshaft, although in certain constructions the speed may be varied when the design of the valve is also varied. The valve 25 is provided opposite each cylinder with a short circumferential recess 27 of 136

a width equal to the width of the intake ports 15 and by-pass ports 17. From this recess are extended two companion recesses, each of a width corresponding with the width of the piston ports 14 before referred to. The ports 20 leading from the gas manifold 19 to the interior of the valve chamber 16 are each of a width equal to the width of one of the recesses 27; while the ports 23 are of a width somewhat less than the width of the valve between the companion recesses 28 before described. The reason for this peculiar structure will appear hereinafter.

15 The piston ports 14 are always in register with the intake ports 15; while the by-pass port 17 is cut off from the interior of the piston when the piston is at the lower end of its movement.

20 For the purpose of forming an induction chamber within each piston, there is provided a closed-end cylindrical device marked 29 which is provided with a flange 30, this flange being countersunk in a suitable counter bore in the lower end of the cylinder 3. The end of the device 29 projecting below the flange 30 is piloted in a suitable aperture in the crankcase 1. This construction is clearly shown in Fig. 1 and further description is deemed unnecessary and is therefore omitted in the interest of brevity. It will be readily understood that by means of this construction, accurate alignment of the device 29, concentrically with the cylinder 3 and the piston 13, is insured. The device 29 is provided with a suitable stuffing-box, marked 31, of well known character. Secured in bosses 32 formed in the piston 13 is a pin 33 and upon 40 this pin is mounted a piston rod 34. This piston rod projects through the stuffing-box 31 before referred to and is threaded into a head 35 located below the stuffing-box. This head 35 also carries a wristpin 36. The lower end of the piston rod 34 is transversely grooved at 37 and the middle section of the wristpin 36 is transversely grooved at 38. Engaging these grooves is a tapered bolt 39, this bolt being fitted into the head 35 before referred to. Journalized upon the wristpin 36 is a fork 40 formed on a connecting rod 41, the other end of which is connected with a crankshaft, not shown. The extreme ends of the wristpin 36 are 55 pocketed in short bosses 42 formed on a circular crosshead 43 which works within the device 29 before referred to.

60 The position of the closed end of the induction chamber forming device 29 is such that the clearance space between its head and the head of the piston—when the latter is at the lower end of its stroke—is definitely larger than the clearance space between the piston head and the cylinder head 65 at the upper end of its stroke.

The parts are shown in Fig. 1 in the position corresponding to zero degrees in the cycle of operations of the master cylinder; and Figs. 3 to 10 inclusive illustrate the position of the valve 25 with respect to 70 the several ports at different times during the cycle of operations and indicated in these figures. It is to be understood, however, that by varying the relative positions and proportions of the ports and valve recesses, different timing may be effected; and it is further to be understood that the recesses and the valve opposite the several cylinders are so located with respect to one another as to bring about the cycle of operations in the several cylinders in their proper order.

75 Referring to Fig. 1, it will be seen that at the time the piston is at the top of its movement, zero degrees in the cycle, the gas manifold 19 is in open communication—through the manifold port 20, the companion recesses 28, the intake port 15, and the piston port 14—with the induction chamber formed within the piston 13. At 80 20 degrees in the cycle of operations, Fig. 3, this communication is cut off. At this time the piston is traveling downward on the power stroke. After the intake is cut off at 20 degrees, compression of the charge in the induction chamber of the piston begins. At 85 117 degrees, Fig. 4, the piston begins to uncover the exhaust port 18 and the burned gas begins to blow out through this port. At this time, the by-pass port 17, the intake port 15, and gas manifold port 20, are all 90 cut off by the valve. At 127 degrees, Fig. 5, the piston has begun to uncover the by-pass port 17. It will be noted that at this time, the recess 27 is almost in position to open 95 the air manifold port 23 to the by-pass port 17. At 135 degrees, Fig. 6, the piston has uncovered more of the by-pass port 17 and the recess 27 of the valve is in position to 100 open communication between the air manifold 23 and the by-pass port 17. At this time, clean air begins to flow from the air manifold where it is maintained under pressure into the combustion chamber of the cylinder above the piston, the pressure of 105 the burned gas within the cylinder having fallen by this time below that of the clean incoming air. The result is that the last traces of the burned gas are expelled from the cylinder and the cylinder is filled with 110 clean air. At 170 degrees, Fig. 7, the valve between the companion recesses 28 cuts off the air manifold port 23 so that 115 no more air flows into the cylinder. At this time, the piston has nearly reached the lower 120 end of its stroke and the fresh charge of gas is compressed in the induction chamber formed within the piston. This gas also fills the intake port 15, through the always registering piston port 14, and is held back by the 125 130

valve 25. The induction chamber clearance is larger than the combustion chamber clearance so that the compression of the gas within the induction chamber is not equal to the compression of gas in the combustion chamber for ignition purposes, but is sufficient to insure a very rapid transfer of the gas from the induction chamber to the combustion chamber. At 180 degrees, Fig. 8, the recess 27 of the valve 25 opens communication between the intake port 15 (and of course the induction chamber) and the combustion chamber above the piston through the by-pass port 17. It will be readily understood that as soon as the crank passes over its lower dead center and the piston begins its upward movement, the pressure within the induction chamber aids this movement. The power expended in the preliminary induction chamber compression is thus in part given back to the engine. At 233 degrees, Fig. 9, the piston has moved upward far enough to cover the by-pass port 17. The flow of gas from the induction chamber to the combustion chamber therefore ceases at this time, and the intake through the gas manifold port 20 begins to open. At 243 degrees, Fig. 10, the piston has moved up far enough to cover the exhaust port 18. From this point to the end of the up stroke, the charge of gas is being compressed in the combustion chamber above the piston and a fresh charge is being drawn into the induction chamber from the gas manifold.

It will be readily understood that the clean air used to drive out the burned gas and thereby scavenge the cylinder is in turn expelled through the exhaust port by the fresh charge of gas rushing from the induction chamber to the combustion chamber and that the burned gas is therefore expelled from the cylinder without waste of fresh gas.

45 What is claimed is:

1. In an internal combustion engine, the combination with a source of gas supply, of a cylinder having a combustion chamber, a piston having a wall port elongated in the direction of piston travel and working within the cylinder, means coöperative with the piston to form an induction chamber within said piston, and means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke.

2. In an internal combustion engine, the combination with a source of gas supply, of a cylinder having a combustion chamber, a piston having a wall port elongated in the di-

rection of piston travel and working within the cylinder, stationary means coöperative with the piston to form an induction chamber within said piston, and means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke. 70

3. In an internal combustion engine, the combination with a source of gas supply, of a cylinder having a combustion chamber, a piston having a wall port elongated in the direction of piston travel and working within the cylinder, a stationary closed-end cylindrical device coöperative with the piston to form an induction chamber within said piston, and means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke. 75

4. In an internal combustion engine, the combination with a source of gas supply, of a cylinder having a combustion chamber, a piston having a wall port elongated in the direction of piston travel and working within the cylinder, a closed-end cylindrical device coöperative with the piston to form an induction chamber within said piston, a cross-head working within said cylindrical device, a piston rod connecting said cross-head with said piston, and means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke. 80

5. In an internal combustion engine, the combination with a source of gas supply, of a cylinder having a combustion chamber, a piston having a wall port elongated in the direction of piston travel and working within the cylinder, means coöperative with the piston to form an induction chamber within said piston and having a clearance definitely larger than that of the combustion chamber, and means continuously coöperative with and controlling the piston port to establish open communication between the induction chamber and the source of gas supply, then confine the charge of gas within the induction chamber substantially to the end of the power stroke, and then effect 115

100

105

its transfer to the combustion chamber during the first part of the return stroke.

6. In an internal combustion engine, the combination with a source of gas supply, of a cylinder having a combustion chamber, a piston having a wall port elongated in the direction of piston travel and working within the cylinder, means coöperative with the piston to form an induction chamber within said piston, means continuously coöperative with and controlling the piston port to establish open communication between the induction chamber and the source of gas supply, then confine the charge of gas

10 within the induction chamber substantially to the end of the power stroke, and then effect its transfer to the combustion chamber during the first part of the return stroke, and means for scavenging the combustion chamber and cylinder with clean air under pressure just prior to the transfer of the fresh charge of gas from the induction chamber to the combustion chamber.

7. In an internal combustion engine, the combination with a source of gas supply, of a cylinder having a combustion chamber, a piston having a wall port elongated in the direction of piston travel and working within the cylinder, means coöperative with 25 the piston to form an induction chamber within said piston, means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke, 30 and means for introducing a charge of clean air into the combustion chamber and cylinder just prior to the transfer of a fresh charge of gas from the induction chamber to the combustion chamber.

45 8. In an internal combustion engine, the combination with a source of gas supply, of a cylinder having a combustion chamber, a piston having a wall port elongated in the direction of piston travel and working within the cylinder, means coöperative with the piston to form an induction chamber within said piston, and valve controlled means continuously coöperative with the piston port to establish open communication between the induction chamber and the source of gas supply, then confine the charge of gas within the induction chamber substantially to the end of the power stroke, and then effect its transfer to the combustion chamber during the first part of the return stroke.

60 9. In an internal combustion engine, the combination with a source of gas supply, of a cylinder having a combustion chamber, a piston having a wall port elongated in the direction of piston travel and working

within the cylinder, means coöperative with the piston to form an induction chamber within said piston, and means continuously coöperative with the piston port and comprising a valve controlled by-pass mechanism and adapted to establish open communication between the induction chamber and the source of gas supply, then confine the charge of gas within the induction chamber substantially to the end of the power stroke, 70 and then establish open communication between the induction chamber and the combustion chamber during the first part of the return stroke.

10. In an internal combustion engine, the combination with a source of gas supply, of a cylinder having a combustion chamber, a piston having a wall port elongated in the direction of piston travel and working within the cylinder, means coöperative with the piston to form an induction chamber within said piston, and a rotary valve and coöperative by-pass mechanism continuously coöperative with the piston port and adapted to establish open communication between the induction chamber and the source of gas supply, then confine a charge of gas within the induction chamber substantially to the end of the power stroke, and then establish open communication between the induction chamber and the combustion chamber during the first part of the return stroke.

11. In an internal combustion engine, the combination with a source of gas supply, of a cylinder having a combustion chamber, a piston having a wall port elongated in the direction of piston travel and working within the cylinder, means coöperative with the piston to form an induction chamber within said piston, a source of clean air supply, and a rotary valve and coöperative by-pass mechanism continuously coöperative with the piston port and adapted to establish open communication between the induction chamber and the source of gas supply, then confine the charge of gas within the induction chamber substantially to the end of the power stroke, establish open communication between the source of clean air supply and the combustion chamber during the last part of the power stroke, and thereafter establish open communication between the induction chamber and the combustion chamber during the first part of the return stroke.

12. In an internal combustion engine, the combination with a cylinder having a combustion chamber and provided with a by-pass port and an intake port in its wall, of a piston working in the cylinder and having a port in its wall always in register with the intake port, means coöperative with the piston to form an induction chamber within said piston, and means for confining the charge of gas within the induction chamber during the last part of the power stroke.

and then effecting its transfer through said ports to the combustion chamber during the first part of the return stroke.

13. In an internal combustion engine, the combination with a cylinder having a combustion chamber and provided with a bypass port and an intake port in its wall, of a piston working in the cylinder and having a port in its wall always in register with the intake port, means coöperative with the piston to form an induction chamber within said piston, and a rotary valve coöperative with the intake and bypass and piston ports to confine the charge of gas within the induction chamber during the last part of the power stroke, and for effecting its transfer through said ports to the combustion chamber during the first part of the return stroke.

14. In an internal combustion engine, the combination with a source of gas supply, of a cylinder having a combustion chamber, a water jacket surrounding the cylinder, a piston having a wall port elongated in the direction of piston travel and working within the cylinder, means coöperative with the piston to form an induction chamber within said piston, and means located mainly beyond the water jacket and continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke.

15. In an internal combustion engine, the combination with a source of gas supply, of a plurality of cylinders each having a combustion chamber, a plurality of pistons working within the cylinders and each having a wall port elongated in the direction of piston travel, means coöperative with each piston to form an induction chamber within said piston, and a single movable member continuously coöperative with and controlling the piston ports to establish in proper order open communication between the induction chambers and the source of gas supply, then confine in proper order charges of gas within the induction chambers substantially to the end of each power stroke, and then effect the transfer in proper order of charges from the induction chambers to the corresponding combustion chambers during the first part of each return stroke.

16. In an internal combustion engine, the combination with a source of gas supply, of a plurality of cylinders each having a combustion chamber, a plurality of pistons working within the cylinders and each having a wall port elongated in the direction of piston travel, means coöperative with each piston to form an induction chamber within said piston, and a rotary valve common to

all of the cylinders and continuously coöperative with and controlling the piston ports to establish open communication in proper order between the induction chambers and the source of gas supply, then confine in proper order charges of gas within the induction chambers substantially to the end of each power stroke, and then effect the transfer in proper order of charges from the induction chambers to the corresponding combustion chambers during the first part of each return stroke.

17. In an internal combustion engine, the combination with a source of gas supply, of a cylinder having a combustion chamber, a piston having a wall port elongated in the direction of piston travel and working within the cylinder, a closed-end cylindrical device countersunk into one end of the cylinder and coöperative with the piston to form an induction chamber within said piston, and means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke.

18. In an internal combustion engine, the combination with a source of gas supply, of a cylinder having a combustion chamber, a piston having a wall port elongated in the direction of piston travel and working within the cylinder, a crankcase supporting the cylinder, a closed-end cylindrical device coöperative with the piston to form an induction chamber within said piston and having a flange between its ends countersunk into the cylinder and clamped between the cylinder and the crankcase and piloted in the crankcase, and means continuously coöperative with and controlling the piston port to establish open communication between the induction chamber and the source of gas supply, then confine the charge of gas within the induction chamber substantially to the end of the power stroke, and then effect its transfer to the combustion chamber during the first part of the return stroke.

19. In an internal combustion engine, the combination with a cylinder having a combustion chamber, of a valve chamber having a port leading into the cylinder, a scavenging air conduit adjacent and having a port leading into the valve chamber, a gas conduit adjacent and having a port leading into the valve chamber, a piston working within the cylinder and having a port adapted to coöperate with the port leading from the valve chamber, means coöperative with the piston to form an induction chamber therein, and a single valve working within the valve chamber and coöperating with the

several ports and arranged and adapted to establish in proper order and timed relation open communication between the combustion chamber and the air conduit, between the induction chamber and the gas conduit, and between the induction and combustion chambers.

20. In an internal combustion engine, the combination with a plurality of cylinders each having a combustion chamber, of a valve chamber common to all of the cylinders and having ports leading thereinto, a scavenging air manifold adjacent and having a port leading into the valve chamber opposite each cylinder, a gas manifold adjacent and having a port leading into the valve chamber opposite each cylinder, pistons working within the cylinders and having ports adapted to coöperate with the ports leading from the valve chamber, means coöoperative with the pistons to form induction chambers therein, and a single valve working within the valve chamber and coöperating with the several ports and arranged and adapted to establish in proper order and timed relation open communication between the combustion chamber and the air conduit, between the induction chamber and the gas conduit, and between the induction and combustion chambers.

21. In an internal combustion engine, the combination with a plurality of cylinders each having a combustion chamber, of a valve chamber extending along one side of and across all of said cylinders and having a series of ports leading into the cylinders, a scavenging air manifold immediately above and having a series of ports leading into the valve chamber one opposite each cylinder, a gas manifold immediately below and having a series of ports leading into the valve chamber one opposite each cylinder, pistons working within the cylinders and having ports adapted to coöperate with the ports leading from the valve chamber, means coöoperative with the pistons to form induction chambers therein, and a single rotary valve working within the valve chamber and coöperating

with the several ports and arranged and adapted to establish in proper order and timed relation open communication between the combustion chambers and the air conduit, between the induction chambers and the gas conduit, and between the induction and combustion chambers. 55

22. In an internal combustion engine, the combination with a cylinder having a combustion chamber, of a valve chamber having a port leading into the cylinder, a gas conduit adjacent and having a port leading into the valve chamber, a piston working within the cylinder and having a port adapted to coöperate with the port leading from the valve chamber, means coöoperative with the piston to form an induction chamber therein, and a single valve working within the valve chamber and coöperating with the several ports and arranged and adapted to establish open communication between the induction chamber and the gas conduit 70 during the induction stroke. 65

23. In an internal combustion engine, the combination with a cylinder having a combustion chamber, of a valve chamber having ports leading into the cylinder in separated position, a gas conduit adjacent and having a port leading into the valve chamber, a piston working within the cylinder and having a port adapted to coöperate with the port leading from the valve chamber, means coöoperative with the piston to form an induction chamber therein, and a single valve working within the valve chamber and coöperating with the several ports and arranged and adapted to establish open communication in proper order and timed relation between the induction chamber and the gas conduit and between the induction and combustion chambers. 75 80

In testimony whereof, I have signed my name to this specification in the presence of two subscribing witnesses.

SYDNEY I. PRESCOTT.
